PUMP

Edward F. Cox and James S. Domingos,
New Bedford, Mass.

Application May 21, 1945, Serial No. 594,840

14 Claims. (Cl. 103—71)

1

This invention relates to a pump, more particularly a bilge pump.

An object of the invention is to provide a bilge pump which may be automatically operated by a rocking motion of a boat or by the wind acting on the pump.

Another object of the invention is to provide rockable means for actuating a pump.

Another object of the invention is the provision of rockable means for moving a pump piston.

Another object of the invention is to harness movement of a boat in any one of a plurality of directions to actuate a pump piston.

With these and other objects in view, the invention consists of certain novel features of construction, as will be more fully described and particularly pointed out in the appended claims.

In the accompanying drawings:

Fig. 1 is a central sectional view of a pump embodying our invention;

Fig. 2 is a plan view of the pump illustrated in Fig. 1;

Fig. 3 is a perspective view of modification showing a staff equipped with a surface to be acted on by the wind;

Fig. 4 is a sectional view illustrating diagrammatically a use of our invention; and

Fig. 5 is a sectional view of a closure.

Referring to the drawing for a more detailed description of the invention, 9 designates generally a pump comprising a cylinder 10 provided with a base 11 having openings 12 for receiving bolts or the like for securing the pump in position. The cylinder is closed at the upper end by a cap 14 having an annular recess 15 in which soft lubricating grease or the like may be placed. A circular opening 16 having tapered walls 17 is provided in the cap and opens into the cavity of the cylinder. The opening 16 is of less diameter than the cylinder cavity and provides an annular shoulder 18. A single inlet and outlet port 19 is provided in the lower portion of the cylinder. However, a separate inlet and outlet may be provided should it be desired.

Mounted for reciprocation in the cavity of the cylinder is a piston 20 which is moved upwardly by means of a tapered coiled compression spring 21 which is interposed between the lower surface of the piston and the bottom wall of the cylinder. In order to move the piston in the opposite direction a semispherical element 22 is provided. This element has a boss 23 extending from the upper flat surface 24 thereof and outwardly through the opening 16. The boss is provided with a bore 25 which receives a staff

26 that is secured in place by a screw bolt 27. The semi-spherical portion 22 is of a size to be loosely received within the cylinder cavity and with the flat surface 24 thereof normally seating against the shoulder 18 and closing the opening 16. A ball 28 is interposed between the member 22 and the piston 20. This ball 28 is seated centrally in the upper surface of the piston in a cavity provided therein. The ball being engageable along the curved surface of the member 22 which provides for transmission of movement therefrom centrally on the piston 20 in all relative positions of the member 22. The wall of the cylinder cavity is lubricated by the lubricant in annular recess 15 escaping through opening 16 when uncovered by the member 22.

When the staff 26 is moved from the normal vertical position to the side of the opening 16, some portion of the peripheral edge of the flat surface 24 will fulcrum along some portion of the shoulder 18. This action will cause portion 22 to rock inwardly as shown in dot-and-dash lines and through the ball 28 move the piston downwardly against the tension of the spring 21. When the staff 26 is free of a moving force the spring 21 is of sufficient strength to return piston and part 22 to the normal position shown in full lines in Fig. 1.

In order to control the direction of flow of fluid to and from the cylinder a valve 30 is provided. This valve comprises generally a body member 31 in the form of a T providing three openings 32, 33, and 34. The valve 30 is connected to the cylinder by means of a nipple 35 which is threadedly received in the opening 34 in the valve body and the port 19 in the cylinder. To the lower opening 32 there is fitted a coupling 36 for attaching thereto a tubular conduit 29 which may be led to the sump to be drained. The upper end or opening 33 is provided with a short nipple 37 which threadedly receives a sleeve 38 to which is fastened a coupling 39 for attaching a tubular conduit 40 for the discharge of fluid from the valve. A ball check 41 is seated in the opening 42 in the coupling 36 on the discharge stroke of the piston. A ball check 43 is carried in the sleeve 38 and is seated in the opening 44 in the nipple 37 on the intake stroke of piston. A slot 45 extends laterally through the lower end of the coupling 39 and provides a port for the passage of fluid through the coupling on the discharge stroke of the piston should the pressure of the fluid be sufficient to seat the ball 43 against the coupling 39. The pump may be manually operated by swin-

ing the staff 28 from side to side of the opening 16 to rock the part 22 in the manner previously described. When the pump is to be automatically operated by the motion of a boat to pump out the bilge the pump is mounted at some convenient location on the boat and spaced from the center thereof in order to utilize the greater motion of the boat at such location. As the boat is set into motion by the action of the waves, the staff 26 will be upset from the vertical by its inertia when the movement in one direction abruptly changes to movement in the other direction and will rock the part 22 and move the piston 20 downwardly causing a discharge of fluid through the conduit 40. When the staff is free of the moving force the spring will return the piston and part 22 to normal initial position providing the intake stroke. In some instances such as very choppy waters it has been found that sufficient time is not had between changes in the direction of the rocking boat to permit the spring to return the piston and part 22 to a substantially normal position. Under such condition the staff 26 may merely swirl about the edge of the opening 16 and prevent rocking motion of the part 22. In order to provide for the proper automatic operation of the pump under such condition we provide a stop 46 comprising a strip 47 extending into the opening 16 and secured to the cap 14 by means of one of the bolts 48 which secures the cap 14 to the cylinder body. Should the motion of the boat be such as to cause the staff 26 to swirl about the edge of opening 16, the stop will interrupt such motion and permit sufficient time for the spring 21 to return the piston 20 and part 22 to normal position.

In some instances we may provide the staff 26 with a flat surface 49 to be acted upon by the wind which is intermittent in force to rock the part 22 about its fulcrum and operate the pump as above described.

A cover 50 is provided when the pump is not in use. This cover may be provided with an opening 51 through which the staff 26 may pass or the staff may be removed if desired.

The term "piston" is herein employed broadly and intended to include a pump plunger of the diaphragm type as well as that shown.

We claim:

1. A pump comprising a cylinder, a piston reciprocally mounted therein, an annular shoulder within said cylinder, a rockable member fulcrumed about said shoulder and extending into said cylinder in sliding engagement with said piston for moving the same upon rocking of said member about said shoulder and means for rocking said member.

2. A pump comprising a cylinder, a piston reciprocally mounted therein, an annular shoulder within said cylinder, a rockable member fulcrumed about said shoulder and extending into said cylinder in sliding engagement with said piston for moving the same in one direction upon rocking of said member about said shoulder, and a spring for moving said piston in the opposite direction and means for rocking said member.

3. A pump comprising a cylinder, a piston reciprocally mounted therein, an annular shoulder within said cylinder, a rockable member fulcrumed about said shoulder having a semispherical portion with the curve surface thereof positioned to engage said piston for moving the same upon rocking of said member about said shoulder and means for rocking said member.

4. A pump comprising a cylinder, a cap at one end of said cylinder providing an annular shoulder, a piston reciprocally mounted in said cylinder, a semi-spherical member within said cylinder with the flat portion thereof fulcrumed about said shoulder and with the curve surface in sliding engagement with said piston for moving the same upon rocking of said member about said shoulder, and means including a staff for rocking 10 said member.

5. In a pump comprising a cylinder, a piston reciprocally mounted therein, fulcrum means, a semi-spherical member rockably mounted about said fulcrum means and extending within said cylinder with the curve surface thereof opposite said piston and in engagement therewith for moving said piston upon rocking of said member and means for rocking said member.

6. A pump comprising a cylinder, a piston reciprocally mounted therein, fulcrum means, rockable means mounted about said fulcrum means and having a surface within said cylinder and in contact with said piston and slideable thereon for moving said piston in one direction and means 20 for rocking said rockable means.

7. A pump comprising a cylinder, a piston reciprocally mounted therein, fulcrum means, rockable means mounted about said fulcrum means and extending within said cylinder having a surface in engagement with and slideable relative to 30 said piston for moving said piston in one direction, and expandible means for moving said piston in the opposite direction and means for rocking said rockable means.

8. A pump comprising a cylinder, a piston reciprocally mounted therein, fulcrum means, rockable means mounted about said fulcrum means and extending within said cylinder having a surface in engagement with and slideable relative to 40 said piston for moving said piston in one direction, a spring for moving said piston in the opposite direction and means for rocking said rockable means.

9. In a pump, a cylinder, a piston reciprocally mounted therein, fulcrum means, and means for moving said piston comprising a member mounted about said fulcrum and having a curved surface in engagement with said piston and slidably related thereto for moving said piston in said cylinder and means for rocking said member.

10. In a pump, a cylinder, a piston reciprocally mounted therein, fulcrum means, and means for moving said piston comprising a semi-spherical member mounted about said fulcrum for rocking 55 movement and engaging said piston for moving the same upon rocking of said semi-spherical member toward said piston and means for rocking said member.

11. In a pump, a cylinder, a piston reciprocally mounted therein, fulcrum means, a member having an enlarged portion rockably mounted about said fulcrum means and engaging said piston for moving the same upon rocking of said member, and means normally extending from said enlarged portion in a vertical direction for rocking said member when upset from the vertical position.

12. In a pump, a cylinder, a piston reciprocally mounted therein, fulcrum means, a member having an enlarged portion confined within the cylinder bore and rockably mounted about said fulcrum means and having a surface thereof engaging said piston for moving the same in one direction upon the rocking of said member, and a spring for moving said piston in the opposite 70 direction and means for rocking said member.

13. In a boat bilge pump comprising a cylinder mounted within a boat, a piston reciprocally mounted within said cylinder, fulcrum means, a rockable member mounted about said fulcrum means and having a surface extending in sliding engagement with said piston and means actuated by the rocking motion of the boat to rock said member to move the piston in one direction and yieldable means for moving said piston in the opposite direction.

14. In a boat bilge pump comprising a cylinder, a piston reciprocally mounted within said cylinder, fulcrum means, a rockable member mounted about said fulcrum means and extending within said cylinder, a staff extending from said member outwardly of the body of the pump and normally

extending vertically and upset by the motion of the boat to rock said member and actuate said piston.
